WILLIAM BURTIS, OF NEW YORK, N. Y.

Letters Patent No. 83,601, dated November 3, 1868.

IMPROVEMENT IN PROPELLER-SHAFTS.

The Schedule referred to in these Letters Patent and making part of the same.

Be it known that I, WILLIAM BURTIS, of the city of New York, in the county of New York, and State of New York, have invented certain new and useful Improvements in the Machinery of Steam Screw-Propellers, namely, a bed-plate abutment, in connection with double counter-shaft gearing; and I do hereby declare that the following is a full, clear, and exact description of the construction and operation of the same, reference being had to the annexed drawings, making a part of this specification, in which—

Figure 1 is a longitudinal sectional view.

Figure 2 is a top view.

Figure 3 is a sectional end view.

A is an abutment of cast-iron, securely fastened to the extended portion of the bed-plate of the engine.

B is the bed-plate of the engine, and B' the extension thereof.

C C are the double counter-shafts.

D is the gear-wheel on the main or wheel-shaft.

E is the gear-wheel on the crank-shaft.

F F F are the gear-wheels on the counter-shafts.

G G G G are pillar-blocks.

H is the main or wheel-shaft.

I is the crank-shaft.

P is the propeller.

a is a collar-thrust.

b is the bearing of the main shaft.

c is a screw for adjusting the main shaft.

d represents a block, of lignumvitæ or brass; concave, against which the main shaft works.

e is the bearing of the crank-shaft.

f represents a liner.

To enable others skilled in the art to make and use my invention and improvements, I will proceed to describe its construction and operation.

I extend the bed-plate B of the engine about twelve feet further aft than those in use at present, and securely fasten thereto a cast-iron abutment, A, against which the main or wheel-shaft H bears, instead of against the engine, as at present. I insert a concave block of lignumvitæ, d, or its equivalent, in the abutment A, in which the end of the main or wheel-shaft revolves, thereby avoiding much friction. Behind the block d, when necessary, I place liners f, which can be adjusted, as desired, by the screw c. The collar-thrust a is the only collar-thrust I use, and it is only

required when backing. I divide the main shaft H I into two separate shafts, termed the crank or engine-shaft H, and the wheel-shaft I. Between these divisions of the shaft, arranged in line with each other, I interpose the abutment A, as aforesaid; and to communicate motion from the engine to the wheel-shaft, I provide the crank-shaft and wheel-shafts, respectively, with gear-wheels D and E. I combine with them two counter-shafts C C, each furnished with gear-wheels F, meshing into the wheels D and E. The latter, and the wheels in the counter-shaft, are varied in size, in the proper proportions, according to the difference of speed or power required for the propeller-wheel with respect to that of the engine.

The pillar-blocks G G G G G, for the main, crank, and counter-shafts are similar to those now in use, and are also sustained by the extension B' of the bed-plate.

The advantages derived from the use of my improved arrangement of abutment and combination of double counter-shaft gearing are as follows:

I am enabled entirely to separate the main shaft from the crank-shaft, and thus do away with the strain and pressure on the engine, which otherwise is incidental thereto, so that the engine and the crank-shaft, once set in line with the wheel-shaft, will always remain in line. I further avoid the friction caused by the roller and collar-thrusts now used, only one collar-thrust (for the purpose of backing) being required. And the strain upon the main and crank-shafts is equalized, as one counter-shaft causes downward pressure while the other is causing upward pressure. Furthermore, in the event of a tooth in the wheel of either counter-shaft breaking, the shaft may be removed and the damage repaired without stopping the engine, except momentarily, to detach the gear-wheels.

What I claim as my invention, and desire to secure by Letters Patent, is—

The application of the double counter-shafts C C with their gear-wheels F, in combination with the gear-wheel E on the crank-shaft, and the gear-wheel D on the wheel-shaft, as herein described.

WILLIAM BURTIS.
